UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,079,930.

Specification of Letters Patent.

Patented Dec. 2, 1913.

Application filed August 27, 1910. Serial No. 579,263.

To all whom it may concern:

Be it known that I, MATTHIAS BROCK, a citizen of the United States, residing at Boston, in the county of Suffolk and State of Massachusetts, have invented certain Improvements in Lasting-Machines, of which the following description, in connection with the accompanying drawings, is a specification, like reference characters on the drawings indicating like parts in the several figures.

This invention relates to lasting machines of the bed type and has for its object to provide a machine having novel provisions for adjustment for right and left crooked lasts.

An advantageous characteristic of this invention is found in the saving of space and convenience of presentation of the shoe to the operator.

As pointed out in prior Letters Patent No. 1,018,477, granted Feb. 27, 1912 on my application, the median lines of the foreparts and heel parts of crooked lasts are usually found to intersect in the forepart of the last and adjustment of the lasting mechanisms relatively to such point of intersection is desirable in order to enable the heel and toe lasting mechanisms to operate symmetrically upon their respective ends of the shoe. In that patent is described a machine having important advantages which is arranged for adjustment of the heel lasting mechanism about a center located at the described point of intersection of said median lines.

One important feature of the present invention consists in mounting an end lasting mechanism for lateral curvilinear movement into different positions about a center which is located at a substantial distance in front of the toe end of the last for the purpose of adapting said mechanism to act similarly upon right and left crooked lasts. As herein shown the toe lasting mechanism is so mounted and the heel lasting mechanism is also laterally adjustable in a curvilinear path.

Various features of this invention relate to the relation of centers about which I have found that movement of the toe and the heel lasting mechanisms may be made with advantageous results. As I am advised, I am the first to provide a machine in which toe and heel lasting mechanisms

are each mounted for lateral curvilinear adjustments and each has its center of movement remote from either end of the shoe, as for example, centers located respectively in front of the toe and of the heel ends of the shoe, with or without connections for adjusting said mechanisms together in constant proportion or in proportions which can be varied for different styles of lasts. It is new by this invention to provide a machine that has toe and heel lasting mechanisms with means by which simultaneous adjustment in predetermined different degrees about two vertical axes having different relations to their respective ends of the last may be effected between the lasting mechanisms and the last.

The illustrated embodiment of this invention by which the whole extent of adjustment required for a crooked last is divided between the two end lasting mechanisms which are displaced in opposite directions but only a short distance from the median line of the machine has the advantage that there is a minimum change of position of the lasting mechanisms relatively to the working position of the operator. He can therefore more conveniently carry on the lasting operation in the manner to which he is accustomed.

Another advantage is found in the economy of factory space required for each machine for obviously a less distance is permissible between machines the working positions of which are confined between narrower limits.

I have found by careful experiment that good results are obtained if the center of movement for the toe lasting mechanism is well in advance of the toe lasting plates, or wipers, for employment with lasts that have the large extent of swing in their forepart that characterizes those in use at the present time. Also the center of movement of the heel lasting mechanism for these lasts should, for the best results as I am now advised, be near the heel lasting plates and it may advantageously be located under the last in about the vertical plane of the heel breast.

By the illustrated connections it is practical with the centers located relatively to the lasting mechanisms substantially as described to adapt the machine for full range of present styles of last in general use with

out adjusting or shifting the centers themselves. The centers of adjustment are preferably found in the carriages which support the end lasting mechanisms and partake of such relative longitudinal adjustment as that of those carriages which is made for different lengths of lasts.

Of course this invention will be readily distinguished from machines such as those 10 of my prior patents for example, in which toe and heel lasting wipers were adjusted angularly to face at an angle to the median line of the machine but were actuated in the median line of the machine rather than 15 in the median lines of the adjacent ends of the last.

These and other features of the invention, including certain details of construction and combinations of parts will be described 20 in connection with the specific embodiment thereof herewith presented and will then be pointed out in the claims.

Figure 1 is a side elevation of a lasting machine embodying this invention; Fig. 2 25 is a plan with the toe and heel lasting mechanisms central of the machine; Fig. 3 is a plan showing the lasting mechanisms adjusted for a left last, the median lines of the machine and of the toe and heel portions 30 of the last being indicated by diverging dotted lines in this figure; Fig. 4 is a detail.

The frame of the machine and the construction and arrangement of the toe and heel end lasting mechanisms may be the 35 same as described in my prior application Serial No. 399,313, or any other suitable type of construction, except as may be hereinafter specified. It may be stated in general that the frame 2 of the machine supports 40 a heel post and a toe rest, the latter of which may conveniently be arranged to slide transversely of the machine or have an extended shoe resting surface adapted to support a shoe with the median line of the 45 last located over said rest at one side of the median line of the machine. The heel lasting mechanism 4 is movable by a hand wheel 5 from and toward the heel post to permit the removal and application of shoes to the post 50 and the desired positioning of said lasting mechanism longitudinally with relation to the heel portion of the shoe. The toe lasting mechanism 6 is carried by a treadle-operated, vertically-movable plunger over the 55 head 8 of which said mechanism is longitudinally adjustable together with the toe rest by a hand wheel 10 toward and from the heel post for lasts of different lengths. The toe lasting mechanism includes lasting 60 plates or wipers 12 which are actuated to do their work by the usual connections with a horizontally swinging hand lever 14. The heel lasting mechanism includes lasting plates or wipers 16 operatively connected 65 with the horizontally swinging lever 18 and

also includes a heel embracing band 20 operatively connected with mechanism controlled or operated by the treadle 22. The toe lasting devices are supported upon a plate 24 which is connected by a vertical pivot 25 with the intermediate plate 26 which is adjusted as above described by a screw and hand wheel 10 longitudinally over the head 8 of the vertically movable plunger. The front end of the plate 24 is curved about the pivot 25 as a center and has a lip over which lies a gib 28 on the plate 26 for holding down and guiding the plate 24. The pivot 25 is located in the median line of the machine at a substantial 70 distance in front of the toe lasting plates or wipers and the adjacent end of the last. 75

The heel lasting mechanism is supported upon a carrier 30 which is pivotally connected to the frame at 35, which is a point located in the median line of the machine, under the last, and at a substantial distance forwardly from the heel end of the last, and preferably substantially under the location 80 of the breast line for the shoe heel. The rear end of the plate 30 is curved about the center 35 and has a lip over which hangs a gib or guiding flange 36 on the frame. 85

The plate 24 of the toe lasting head has a lateral projection at the rear side of the machine which carries a roll or stud standing in a slot in the head 38 of a bar 40, said slot permitting adjustment of the heel lasting head longitudinally without moving the bar 40. The stem of the bar 40 slides freely in 90 guideways formed in a bracket 42 attached to the machine frame, this movement accompanying and being effected by adjustment of the heel lasting devices about the center 35. The bar 40 rigidly supports between its bearings in the bracket 42 a block 45 which has an adjustable connection with the angular end of a lever 46 being fastened in adjusted position by a binding bolt 43. This lever is fulcrumed on the bracket at 47 95 and its long arm is pivoted at 48 to a link 50 which is pivoted to a block 52 attached to the side of the carrier 30 upon which the heel lasting devices are mounted for lateral curvilinear movement about the pivot 35. 100 The block 52 is adjustable lengthwise of the machine by the screw 54. 105

By means of the connection 46, 50 between the toe lasting mechanism and the heel lasting mechanism the two mechanisms 110 are adjusted together or by single adjusting movements, as, for example, by force applied laterally by the hand of the operator to the toe lasting mechanism or the heel lasting mechanism. Also, this connection combined with the location of the pivots 25 and 35 effects movement of the toe lasting mechanism laterally toward one side of the machine and effects movement of the heel lasting mechanism toward the opposite side 115 120 125 130

of the machine. The screw 54 provides means for adjusting the connection between the heel lasting mechanism and the link 50 toward and from the pivot 35 whereby a given lateral movement of the toe lasting mechanism will effect a variable movement of the heel lasting mechanism.

In the use of the machine a shoe will be applied to the supporting devices in the usual way, the lasting mechanism will then be adjusted as, for example, by pushing the toe lasting devices toward the right hand or back side of the machine, as indicated in Fig. 3 for a left shoe, until said devices are positioned symmetrically with relation to the toe end of the shoe. This adjustment of the toe lasting mechanism is accompanied by a lateral curvilinear movement of the toe rest which is attached thereto and to the shoe which is supported at its toe end on said rest. This adjustment is also accompanied by a lateral curvilinear movement of the heel lasting mechanism in the opposite direction or toward the left in Fig. 3. If the block 52 has been properly adjusted for the style of shoe that is to be lasted, this adjustment of the heel lasting mechanism thus effected will position that mechanism symmetrically with relation to the heel portion of the shoe. This adjustment of the block 52 having once been found for a style of last may remain constant until a different style or shape of last is presented. If the adjustment of the heel lasting mechanism is not correct when the toe lasting mechanism has been adjusted into symmetrical relation to the forepart of a last, additional adjustment for the heel lasting mechanism may be effected by manipulation of the screw 54. The links 46 and 50 constitute a sort of toggle.

Having described and explained a machine embodying my invention in its preferred form, which embodiment may, however, be variously modified and is to be regarded as for the purpose of illustration and explanation only, I claim as new and desire to secure by Letters Patent of the United States:—

50. 1. A lasting machine having, in combination, a pivotally mounted toe lasting mechanism and a pivotally mounted heel lasting mechanism arranged for lateral turning movement about centers which are located respectively a substantial distance in front of the toe and the heel ends of the shoe for adaptation to a right or a left crooked last.

2. A lasting machine having, in combination, last supporting means, a pivotally mounted toe lasting mechanism and a pivotally mounted heel lasting mechanism connected together for simultaneous movement laterally of the machine in opposite directions relatively to the last supporting means and about separate centers, one of which is

located in advance of the adjacent end of the last.

3. A lasting machine having, in combination, toe and heel lasting mechanisms which are mounted for movement laterally of the machine about centers which are located remote from the ends of the last to adapt both mechanisms for operation on a right or a left crooked last occupying a single position.

4. A lasting machine having, in combination, toe and heel lasting mechanisms which are connected together for simultaneous adjustment laterally in opposite directions about centers located respectively in front of the toe and the heel ends of the last.

5. A lasting machine having, in combination, toe and heel lasting mechanisms which are connected together for simultaneous adjustment laterally about axes which are located respectively in front of the toe and substantially at the breast of the heel and in directions which are opposite and degrees which are relatively variable.

6. A lasting machine having, in combination, pivotally mounted toe and heel lasting mechanisms connected together for simultaneous lateral adjustment about axes located respectively a substantial distance in front of the toe and under the breast of the heel, said connections being arranged to permit variation in the length of adjustment of one of said parts while the other is moved a definite distance.

7. A lasting machine having, in combination, an end lasting mechanism mounted for curvilinear lateral adjustment about a center located outwardly beyond the adjacent end of the last, and a second end lasting mechanism mounted for lateral curvilinear movement about a center that is located inwardly under the adjacent end of the last.

8. A lasting machine having, in combination, an end lasting mechanism which is mounted for lateral curvilinear movement into different operative positions for the purpose described about a center which is located at a substantial distance in front of the toe end of the shoe.

9. A lasting machine having, in combination, a heel lasting mechanism that is laterally adjustable in a curvilinear path, and a toe lasting mechanism which is laterally adjustable about a center located a substantial distance in front of the last in the machine.

10. A lasting machine having, in combination, a heel lasting mechanism that is laterally adjustable in a curvilinear path, a toe lasting mechanism which is laterally adjustable about a center located a substantial distance in front of the last in the machine, and means connecting said two mechanisms for effecting simultaneous lateral adjustments thereof.

11. A lasting machine having, in combination, toe and heel lasting mechanisms each mounted for lateral curvilinear adjustment and having its center of movement remote 5 from either end of the shoe.
12. A lasting machine having, in combination, toe and heel lasting mechanisms each mounted for lateral curvilinear adjustment and having its center of movement remote 10 from either end of the shoe, and connections for adjusting said mechanisms together.
13. A lasting machine having, in combination, toe and heel lasting mechanisms each mounted for lateral curvilinear adjustment 15 and having its center of movement remote from either end of the shoe, connections for adjusting said mechanisms together, and connections for effecting predetermined proportional adjustments which can be relatively varied for the two mechanisms.
14. A lasting machine having, in combination, toe and heel lasting mechanisms which are relatively adjustable into different operative positions for the purpose described 25 laterally about two centers, one of which is located under the last and one of which is located outwardly beyond an end of the last.
15. A lasting machine having, in combination, toe and heel lasting mechanisms, and means for relatively moving said two mechanisms simultaneously about two vertical axes which are, respectively, differently located relatively to the toe and to the heel 35 of the last to permit positioning of each mechanism in symmetrical lateral relation to its adjacent last end.
16. A lasting machine having, in combination, toe and heel lasting mechanisms, and 40 means whereby simultaneous adjustment in predetermined different degrees about two vertical axes having different relations to their respective ends of the last may be effected between the lasting mechanisms and 45 the last.
17. A lasting machine having, in combination, a heel lasting mechanism, a toe lasting mechanism which is movable laterally about a center located in advance of the toe end of the last into working position at opposite sides of the median line of the machine, and a toe rest arranged to permit the toe portion of right and left crooked lasts to be positioned at opposite sides of the median line of the machine for presentation symmetrically to the toe lasting mechanism. 50
18. A lasting machine having, in combination, shoe supporting means constructed and arranged to support a shoe with the longitudinal axis of the last oblique to the median line of the machine, and toe and heel lasting mechanisms mounted for curvilinear lateral adjustments about centers having different relations respectively to the adjacent last ends into positions to act symmetrically upon the fore parts and heel parts of lasts so supported. 55
19. A lasting machine having, in combination, the toe lasting mechanism 6, the heel lasting mechanism 4, the link 50 connected to the heel lasting mechanism, the lever 46 connected to said link and having a fixed fulcrum and the slide 40 connecting the toe lasting mechanism to said lever. 60
20. A lasting machine having, in combination, the toe lasting mechanism and heel lasting mechanism, connections between said mechanism for making lateral adjustments thereof, and the sliding connection 24, 38 to permit variation in the lengthwise position of the toe lasting mechanism for shoes of different sizes without disturbing the adjusting connections. 65

In testimony whereof I have signed my name to this specification in the presence 70 of two subscribing witnesses.

MATTHIAS BROCK.
